In Great Britain November 10, 1949

Term of patent 14 years

(Cl. D14—3)

To all whom it may concern:

Be it known that I, Hiram Henry Williams, a subject of the King of Great Britain, residing at 7, Heol-y-Bryn, Rhiwbina, Cardiff, in the county of Glamorgan, Wales, have invented a new, original, and ornamental Design for a Hand Truck, of which the following is a specification, reference being had to the accompanying drawings, forming part thereof.

I claim:

The ornamental design for a hand truck, as shown.

HIRAM HENRY WILLIAMS.
